FUEL PRESSURE RESPONSIVE BURNER
CONTROLLING APPARATUS

Fred B. Aubert, Detroit, Mich.

Application November 1, 1945, Serial No. 626,034

25 Claims. (Cl. 158—28)

1

This invention relates to new and useful improvements in apparatus for controlling the operation of fluid fuel burners.

An object of the invention is to provide means for stopping the supply of fuel to the burner upon extinguishment of the burner flame.

Another object is to provide an apparatus in which burner operation is dependent upon predetermined fuel pressure.

Another object is to provide means by which the burner operating motor is deenergized upon initial occurrence of flame and is reenergized by predetermined fuel spraying pressure.

Another object is to provide electron tube safety means for controlling burner operation.

Another object is to provide means to delay the start of burner operation until the safety means is conditioned for operation.

The invention consists in the cooperative relation and sequential operation of the parts of the apparatus, to be more fully described hereinafter, and the novelty of which will be particularly pointed out and distinctly claimed.

In the accompanying drawing, to be taken as a part of this specification, there is fully and clearly shown a preferred embodiment of the invention, in which drawing, the figure is a diagrammatic view of the fuel burner controlling apparatus.

Referring to the drawing by characters of reference, 1 designates generally a heating apparatus such as a boiler or furnace having a burner 2 with a combustion air delivery tube 3 supplied with air by a fan 4 driven by an electric motor 5. A liquid fuel pump 6 is driven by the motor 5 through suitable gearing and has its inlet connected to a fuel pipe 7 leading from a source of fuel such as a tank. The pump 6 discharges through a pipe 8 to a fuel nozzle 9 for spraying fuel into the air supplied by the tube 3. Ignition electrodes 10 are provided to ignite the discharging fuel and are supplied with current from the secondary coil of their ignition transformer 11. The heating apparatus 1 is provided with the usual safety limit switch 12 responsive to temperature or pressure of the heat exchange medium in the boiler or furnace and operable to stop the motor 5 at the desired maximum safe limit or temperature.

Connected into the fuel pipe 8 there is a pressure conveying pipe 13 connected to the pressure chamber 14 of a pressure responsive switch device 15. The chamber 14 which preferably contains air is closed and sealed by a diaphragm 16 which is held against movement by pressure in the

chamber 14 by a spring 17 which exerts a pressure of say sixty pounds per square inch in opposition to movement of the diaphragm 16 by the chamber pressure. The pipe 13 is preferably a so called capillary tube and is of sufficiently small bore so as to delay the transmission of pressure from the pipe 8 to the diaphragm 16. Further delay of pressure transmission to the diaphragm 16 is accomplished by the air cushion in the chamber 14. The diaphragm 16 actuates a switch operating rod 18 which may be of electric insulating material and which is operatively connected to snap acting switch arms 19 and 20 such that the arms are moved in unison. The arm 19 operates a normally closed switch 21 which controls the ignition transformer 11 and the circuit of a resistance heater 22 of a timer or warp switch 23. The arm 19 also controls the normally closed contacts of a tube relay controlling switch 24. Cooperable with the arm 19 there is a holding magnet 25 which is energized upon closure of a normally open switch 26 controlled by the arm 19. The arm 20 controls a normally closed motor starting switch 27 and a normally open motor running circuit switch 28.

The motor 5 is energized from main line wires 29 and 30 of which the wire 30 is the ground wire. In the line wire 29 there is a switch 31 which is closed during the heating season and which is opened solely when it is desired to deenergize the entire control apparatus and burner. Connected across the main line wires is the primary coil 32 of a step down transformer 33 having a tube filament heating secondary coil 34 supplying say 6 volts and a control circuit secondary coil 35 supplying about 24 volts. Leading from one terminal of the coil 35 there is a lead wire 36 connected to one terminal of the relay operating coil 37 of a main relay control switch 38 which is normally open and controls the operation of the motor 5 and the ignition transformer 11. From the other terminal of the relay coil 37 a lead wire 39 connects to the temperature responsive bimetal arm 40 of an automatic control switch 41 such as a room thermostat. The arm 40 cooperates with a fixed switch contact 41^a connected by a lead wire 42 to one terminal of an electron tube 43 functioning as a time delay switch which has its other terminal connected by a lead wire 44 to a lead wire 45 which connects to the other terminal of the secondary coil 35. The tube 43 is preferably, as shown, an electron tube having its anode 46 connected to the wire 42 and having its cathode 47 which is heated by the filament 48, connected

to the wire 44. The grids 49 are connected together and to the wire 42 by a wire 50 so that the tube becomes conducting when the cathode 47 is heated to operating temperature by the filament 48. The filament 48 is connected by lead wires 51 and 52 to the lead wires 53 and 54 respectively, which are connected respectively to the end terminals of the transformer secondary coil 34. Connected between the wires 36 and 53 there is a fixed condenser 55. The tube 43 is of the same type or has the same energizing or cathode heating time as the electron control tube 56 which is preferably of the gas charged trigger type such as an R. C. A. No. 2051. The filament 57 is connected by lead wires 58, 59 to the transformer secondary coil 34 by the lead wires 53, 54 respectively. The tube 56 controls the circuit of the relay coil 60 of a double throw relay switch having a normally closed motor starting switch 61 and a normally open motor running and relay coil holding switch 62. The coil 60 has one terminal connected to the switch 62 by lead wires 63, 64 and to the fixed contact of the pressure operated switch 24 by lead wires 64, 65, 66. The other terminal of coil 60 is connected by a lead wire 67 to one terminal of a resistance 68 which has its other terminal connected by a lead wire 69 to the anode 70. The cathode 71 is connected by a wire 72 to the filament wire 58 and thence through wire 53 and a wire 73 to the ground wire 30. The screen grid 74 is connected to one terminal of a resistor 75 which has its other terminal connected by a lead wire 76 to the cathode lead wire 72. The other resistor terminal is also connected by a lead wire 77 to one terminal of a resistor 78 having its other terminal connected to ground, as at 79. A third lead wire 80 connects the other terminal of resistor 75 to one side of a fixed condenser 81 having its other side connected by a lead wire 82 to the relay coil wire 67. The control grid 83 is connected by a lead wire 84 to a lead wire 85 which is connected to the cathode 86 of a photo-electric cell 87 having its anode 88 connected to ground as at 89 by a lead wire 90. The cell 87 is housed and is provided with a sight tube 91 aimed at the area of the burner flame of the burner 2 so as to respond to the occurrence and failure of flame. The cell housing shields the cell 87 from response to any other light than that of the burner flame. The control grid lead wire 84 is connected by a lead wire 92 to one side of a variable condenser 93 which has its other side connected by a lead wire 94 to the lead wire 45 which connects to the secondary coil 35 so that the control grid 83 is negatively biased. The shield grid 74 which has its negative bias determined by the resistor 75, determines the extent to which the control grid 83 must become more positive or less negative in order for the tube 56 to be conductive. The variable condenser 93 determines the extent of negative drain necessary upon conductivity of the photo-cell 87 in order to overcome the bias of the grid 83.

The timer or warp switch 23 is of the conventional type having normally closed contacts 95 movable to open position by a bimetal operating arm 96 heated by the resistance coil 22. The arm 96 is locked in open position by a spring pressed manually released latch member 97 which operates in the usual manner to hold the contacts 95 in position when they have been separated by the operation of the blade 96.

The operation of the control apparatus and

burner is as follows: The switch 31 is closed to place the control apparatus in operation. However the operating circuit for the main control switch 38 will only be completed after sufficient time delay necessary to heat the filament 57 of the control tube 56 because the switch tube 43 requires the same heating time for its filament 48 as does the filament 57 before the circuit can be completed through the relay coil 37. Although this operation occurs at the beginning of a heating season upon closure of switch 31, the primary purpose of the tube 43 is to assure sufficient warming up of the control tube 56 following a main line current failure so that the burner motor cannot be started until the control tube 56 is properly responsive to occurrence of flame at the burner. Assuming that the tube 43 has heated up sufficiently to be current conductive then upon a call for heat by the room thermostat which closes switch 41, the relay coil 37 will be energized to close the main switch 38 by the following circuit; from the secondary coil 35 through wire 36 to coil 37 thence through wire 39, closed switch 41 and wire 42 to the anode 46 and thence through the tube 43 to the cathode 47 and by lead wires 44, 45 back to the transformer coil 35. Closure of the main switch 38 will start operation of the burner motor 5 through the closed limit switch 12, timer switch 95 and starting switches 61 and 27 by the following motor starting circuit: from line wire 29 through closed switch 31 and wire 98 to the closed limit switch 12, thence by lead wire 99 to the closed timer switch 95, from timer switch blade 96 via lead wire 100 to the fixed contact of main switch 38 thence through wires 101 and 102 to the switch arm of the tube relay closed starting switch 61, through wire 103 to the fixed contact of starting switch 27, from the switch blade 20 via lead wire 104 to one terminal of the motor 5 and from the other motor terminal via wire 105 to the wire 30 which is at ground potential. Closure of the main switch 38 also closes the ignition transformer circuit simultaneously with the closure of the motor starting circuit, the ignition circuit being as follows: From switch 38 and lead wire 101 through lead wire 106 to switch arm 19, through closed switch 21 to lead wire 107 and thence through lead wire 108 to one terminal of the ignition transformer primary coil 109 having its other terminal connected by wire 110 to the wire 30. Main switch 38 also simultaneously closed the circuit for the timer switch resistance heater 22 via the following circuit: from switch 38 via lead wires 101, 106, switch 21, lead wire 107 and lead wire 111 to one terminal of the heater coil 22 and from the other coil terminal via wire 112 to the wire 30. Switch 38 also prepared the tube relay circuit for current flow upon the tube 56 becoming conductive in response to occurrence of flame at the burner. Operation of the motor 5, due to closure of switch 38, drives the pump 6 to build up pressure in the nozzle supplying pipe 8 and as soon as the pressure is sufficient, at say forty pounds per square inch, to discharge an ignitable spray of fuel, the spark ignition occurring between the electrodes 10 will ignite the fuel. Instantly that flame occurs at the burner, the photo-cell 87 will become conductive thereby driving the control grid 83 sufficiently toward positive so that the tube 56 becomes conductive. Instantaneously with the occurrence of flame, the relay coil 60 will therefore be energized through the following circuit: from main switch 38 through wires 101, 106,

switch arm 19, closed switch 24, wires 66, 65 and 64 to the coil 60 and thence via wire 61, resistor 68, wire 69 to anode 70, through the tube 56 to cathode 71 and via wires 72, 58, 53 and 73 to the wire 30. Energization of coil 60 breaks the motor starting circuit at switch 61 and closes switch 62 preparatory to closure of switch 28 to complete the running circuit of the motor. Closure of switch 62 has closed the holding circuit for the coil 60 through the tube 56, this circuit being from main switch 38 through wires 101 and 102 to the now closed switch 62 and thence via wires 63 and 64 to the coil 60 from which the circuit continues through the tube 56 to the wire 30, as above described. Assuming that the pump 6 is operating normally, the build up of pressure in the pipe 8 from the forty pounds per square inch at which flame occurred to the minimum safe operating fuel pressure of say sixty pounds per square inch will occur in about one second or less and this occurrence of operating pressure will, even though delayed by the resistance of the tube 13 and the air cushion in chamber 14, actuate the snap acting switch arms 19 and 20 preferably within one second from the time of opening of the motor starting switch 61. Although the motor is deenergized during this interval after opening of switch 61, the motor inertia is sufficient to maintain and build up pressure so that the flame will not become extinguished in normal operation. Operation of the switch device 15 closes the motor running switch 28 so that the motor 5 is reenergized through the following circuit: from main switch 38 via wires 101, 102 to closed switch 62, wires 63, 65 and 113 to the now closed running switch 28, then via switch blade 20 and wire 104 to one terminal of the motor 5 which has its other terminal connected by wire 105 to the wire 30. Operation of the switch device 15 also opens the switch 21 to break the circuit to the ignition transformer primary coil 109 and to the timer resistance heater 22. In addition, the operation of the switch arm 19 opens the switch 24 to break the first circuit through lead wires 66, 65 and 64 to the tube relay coil 60 which however is maintained energized as above described through the now closed switch 62. The switch arms 19 and 20 are held in their pressure operated position by the holding magnet 25 which is cooperable with the switch arm 19, the magnet 25 being energized by closure of switch 26 through the following circuit: from switch 38 via wires 101, 106, switch arm 19, closed switch 26, wire 114 to the magnet coil 25 and thence via wire 115 to the wire 30. The burner motor 5 will now continue in operation to heat the apparatus 1 until the main switch 38 is opened by opening of the control switch 41. Should there be a failure of flame during normal burner operation after the pressure switch device 15 has functioned to close the circuit of the magnet holding coil 25, the electron control tube 56 will be instantly blocked against current flow between the anode and cathode by the control grid 83 thereby deenergizing the relay coil 60 so that the switch 62 will be opened and the switch 61 will be closed. Opening of switch 62 breaks the circuit through which the coil 60 was maintained energized and since the first circuit at switch 24 through which the coil 60 was originally energized is held broken by the magnet coil 25, the motor circuit cannot be re-established even though there might be a reoccurrence of flame at the burner. If, during burner starting operation, flame does not occur

before pressure builds up in the pipe 8 to the minimum desired sixty pounds spraying pressure, then the switch device 15 will open the motor starting circuit at the switch 27 and also break the energizing circuit for the tube relay coil 60 at the switch 24 and since the magnet 25 is simultaneously energized by closure of switch 26, the motor circuit will be held open until the main switch 38 is opened to deenergize the magnet coil 25. If, when there is a call for heat, pressure does not build up to the minimum desired operating pressure within the time limit of say sixty seconds required for operation of the safety warp or timer switch 23, then the contacts 95 will be opened and locked open by the latch 97 thereby breaking the motor circuit and preventing starting of the burner motor until the reset button 116 has been actuated to release the bimetal arm 26 for reclosure of the contacts 95. When the switch 41 is opened as will occur when the room thermostat is satisfied by the ambient temperature reaching the desired degree, the coil 37 will be deenergized thereby opening the main switch 38 to deenergize the burner. The opening of switch 38 will deenergize the holding coil 25 so that the switches of the pressure device 15 return to the position shown in the drawing and will also deenergize the relay coil 60 so that the switches 61 and 62 return to their shown position, thus placing the system in condition for a new cycle of burner operation when the switch 41 is again closed.

What is claimed and is desired to be secured by Letters Patent of the United States is:

- 35 1. A liquid fuel burning apparatus, comprising a burner, a pump for supplying liquid fuel under pressure to the burner, a motor for driving said pump, a starting circuit for said motor, means to close said circuit, means to ignite the fuel discharged at said burner, means instantly acting upon occurrence of flame at said burner to break said starting circuit, a running circuit for said motor, two open switches in said running circuit, said instantly acting means acting also to close one of said two switches, and means responsive to predetermined fuel pressure and operable to close the other of said running circuit switches to establish current flow through said motor.
- 40 2. A liquid fuel burning apparatus, comprising a burner, a pump for supplying liquid fuel under pressure to the burner, a motor for driving said pump, a starting circuit for said motor, a pair of normally closed switches in said circuit, a running circuit for said motor, a pair of normally open switches in said running circuit, a switch controlling current flow to said circuits, means to ignite the fuel discharged at said burner, means instantly acting upon occurrence of flame at said burner to open one of said normally closed switches and to close one of said normally open switches, and means responsive to predetermined fuel pressure and operable to open the other of said normally closed switches and to close the other of said normally open switches.
- 45 3. A liquid fuel burning apparatus, comprising a burner, a pump for supplying liquid fuel under pressure to the burner, a motor for driving said pump, a starting circuit for said motor, means to close said circuit, means to ignite the fuel discharged at said burner, a relay switch having normally closed contacts in said starting circuit, electron tube control means instantly acting upon occurrence of flame at said burner to actuate said relay switch to break said start-

ing circuit, a running circuit for said motor, an open switch in said running circuit, means responsive to predetermined fuel pressure and operable to close said running circuit switch; and means operable, upon actuation of said pressure responsive means, to hold said running circuit switch closed independently of said pressure responsive means.

4. A liquid fuel burning apparatus, comprising a burner, a pump for supplying liquid fuel under pressure to said burner, a motor for driving said pump, means to ignite the fuel discharged at said burner, a starting circuit for said motor, means to close said circuit, a running circuit for said motor, a pair of normally open switches in said running circuit, means instantly acting upon occurrence of flame at said burner to break said starting circuit and to close one of said running circuit switches, fuel pressure operated means to close the other of said running circuit switches; and means operable, upon actuation of said pressure responsive means, to hold said other running circuit switch closed independently of said pressure operated means.

5. A liquid fuel burning apparatus, comprising a burner, a pump for supplying liquid fuel under pressure to said burner, a motor for driving said pump, means to ignite the fuel discharged at said burner, a starting circuit for said motor, means to close said circuit, a running circuit for said motor, a pair of normally open switches in said running circuit, means instantly acting upon occurrence of flame at said burner to break said starting circuit and to close one of said running circuit switches, fuel pressure operated means to close the other of said running circuit switches, a switch in said starting circuit and opened by said fuel pressure operated means, and means to hold said last-named switch open so that flame failure will not restart said motor.

6. A liquid fuel burning apparatus, comprising a burner, a pump for supplying liquid fuel under pressure to said burner, a motor for driving said pump, means to ignite the fuel discharged at said burner, a starting circuit for said motor, a running circuit for said motor, relay switch means having a closed switch in said starting circuit and an open switch in said running circuit, first and second circuits for energizing said switch means, said open switch controlling said second switch means energizing circuit, an electron tube responsive to burner flame and blocking current flow through said first and said second switch means energizing circuits, a switch controlling current flow through said circuits, a closed switch in said first switch means energizing circuit, means cooperable with said tube and instantly acting upon occurrence of a burner flame to render said tube conductive thereby to energize said switch means to open said closed starting circuit switch and to close said open running circuit switch, a second closed switch in said starting circuit, means responsive to predetermined fuel pressure and operable to open said second-named closed switch and said last-named switch; and means operable, upon actuation of said pressure responsive means, to hold open said second-named closed switch and said last-named switch.

7. A liquid fuel burning apparatus, comprising a burner, a pump for supplying liquid fuel under pressure to the burner, a motor for driving said pump, a starting circuit for said motor, an ignition means circuit in parallel with said starting circuit, electric ignition means in said ignition

means circuit and operable to ignite the fuel discharged at said burner, a closed controlling switch in said parallel ignition means circuit, a main switch operable to close said starting circuit and said ignition means circuit, a switch in said parallel starting circuit, means instantly acting upon occurrence of a burner flame to open said last-named switch to break said starting circuit, a running circuit for said motor, an open switch in said running circuit, and means responsive to predetermined fuel pressure and operable to close said running circuit switch and to open said ignition means controlling switch.

8. A liquid fuel burning apparatus, comprising a burner, a pump for supplying liquid fuel under pressure to the burner, a motor for driving said pump, a starting circuit for said motor, means to ignite the fuel discharged at said burner, electric timing means having a switch controlling current flow to said motor and having a controlling circuit, a closed switch in said controlling circuit, a main switch to close said starting circuit and said controlling circuit, means instantly acting upon occurrence of a burner flame to open said starting circuit, a running circuit for said motor, two open switches in said running circuit, said instantly acting means acting upon occurrence of flame to close one of said two switches, and means responsive to predetermined fuel pressure and operable to close the other of said running circuit switches and to open said closed controlling circuit switch.

9. A liquid fuel burning apparatus, comprising a burner, a pump for supplying liquid fuel under pressure to the burner, a motor for driving said pump, a starting circuit for said motor, electric ignition means for the fuel discharged at said burner and having an energizing circuit, electric timing means having a switch controlling current flow to said motor and having a controlling circuit, a closed switch in said energizing circuit and in said controlling circuit, a main switch to close said starting circuit, to close said energizing circuit for said ignition means and said controlling circuit, means instantly acting upon occurrence of a burner flame to open said starting circuit, a running circuit for said motor, an open switch in said running circuit and closed by said instantly acting means, a second open running circuit switch, and means responsive to predetermined fuel pressure and operable to close said second-named running circuit switch and to open said closed controlling and energizing circuit switch.

10. A liquid fuel burning apparatus, comprising a burner, a pump for supplying fuel under pressure to said burner, an electric motor for driving said pump, a starting circuit for said motor, a running circuit for said motor, an ignition circuit having burner igniting electrodes, a relay switch coil energizing circuit, a relay switch coil holding circuit, a warp switch heater circuit, a holding magnet circuit, a main relay switch controlling all of said circuits, a relay switch having closed contacts in said starting circuit and open contacts in said coil holding and running circuits and having its coil in said coil energizing and holding circuits, an electron tube responsive to burner flame and in said coil energizing and holding circuits and having a control grid blocking current flow therethrough, means instantly acting upon occurrence of flame at said burner to render said grid sufficiently positive for current flow through said tube, a pressure switch responsive to fuel pressure and having

closed contacts in said starting circuit and open contacts in said running circuit, said pressure switch having closed contacts in said coil energizing circuit and in said ignition and heater circuits and having open contacts in said magnet circuit, a holding magnet in said holding magnet circuit and operable to hold said pressure switch in pressure actuated position, a warp switch controlling current flow to the switch contacts of said main relay switch and having a resistance heater in said heater circuit, and a control switch in circuit with the coil of said main relay switch.

11. A liquid fuel burning apparatus, comprising a burner, a pump for supplying fuel under pressure to said burner, an electric motor for driving said pump, a starting circuit for said motor, a running circuit for said motor, an ignition circuit having burner igniting electrodes, a relay switch coil energizing circuit, a relay switch coil holding circuit, a warp switch heater circuit, a holding magnet circuit, a main relay switch controlling all of said circuits, a relay switch having closed contacts in said starting circuit and open contacts in said coil holding and running circuits and having its coil in said coil energizing and holding circuits, an electron tube responsive to burner flame and in said coil energizing and holding circuits and having a control grid blocking current flow therethrough, means instantly acting upon occurrence of flame at said burner to render said grid sufficiently positive for current flow through said tube, a pressure switch responsive to fuel pressure and having closed contacts in said starting circuit and open contacts in said running circuit, said pressure switch having closed contacts in said coil energizing circuit and in said ignition and heater circuits and having open contacts in said magnet circuit, a holding magnet in said holding magnet circuit and operable to hold said pressure switch in pressure actuated position, a warp switch controlling current flow to the switch contacts of said main relay switch and having a resistance heater in said heater circuit, a control switch in circuit with the coil of said main relay switch, and means maintaining said last-named circuit open until said electron tube is at operating temperature.

12. A fuel burning apparatus, comprising a burner, a conduit for supplying fuel to said burner, means responsive to fuel pressure in said conduit, electrically energized means controlling the supply of fuel through said conduit, a circuit for initially energizing said electrically energized means to supply fuel, means to ignite the fuel discharged at said burner, means instantly acting to break said circuit upon occurrence of flame at said burner, an operating circuit for said energized means, and two open switches in said operating circuit, said instantly acting means acting also to close one of said two switches, said responsive means acting to close the other of said two switches to establish current flow through said operating circuit to said energized means; and means operable, upon actuation of said pressure responsive means, to hold said other switch closed independently of said responsive means.

13. In a liquid fuel burning apparatus, a burner, a pump for supplying fuel under pressure to said burner, a motor for driving said pump, means to ignite the fuel discharged at said burner, a motor starting circuit, a motor running circuit, relay switch means having a normally closed switch in said starting circuit and a nor-

mally open switch in said running circuit and operable when energized to open said closed switch and to close said open switch, first and second energizing circuits for energizing the coil of said relay switch means, said second coil energizing circuit being closed upon energization of said relay coil and maintaining said relay coil energized upon breaking of said first coil energizing circuit, electron tube control means blocking current flow through said first and said second coil energizing circuits and instantly acting upon occurrence of flame to permit current flow through said first coil energizing circuit, and means operable by predetermined fuel pressure to open said first coil energizing circuit and to close said running circuit.

14. A liquid fuel burning apparatus, comprising a burner, a pump for supplying liquid fuel under pressure to the burner, a motor for driving said pump, a starting circuit for said motor, means to close said circuit, means to ignite the fuel discharged at said burner, means instantly acting upon occurrence of flame at said burner to break said starting circuit, a running circuit for said motor, two open switches in said running circuit, said instantly acting means acting also to close one of said two switches, means responsive to predetermined fuel pressure and operable to close the other of said running circuit switches to establish current flow through said motor, and means operable, upon actuation of said pressure responsive means, to hold said other running circuit switch closed independently of said pressure responsive means.

15. A liquid fuel burning apparatus, comprising a burner, a pump for supplying liquid fuel under pressure to the burner, a motor for driving said pump, a starting circuit for said motor, a pair of normally closed switches in said circuit, a running circuit for said motor, a pair of normally open switches in said running circuit, a switch controlling current flow to said circuits, means to ignite the fuel discharged at said burner, means instantly acting upon occurrence of flame at said burner to open one of said normally closed switches and to close one of said normally open switches, means responsive to predetermined fuel pressure and operable to open the other of said normally closed switches and to close the other of said normally open switches, and means operable, upon actuation of said pressure responsive means, to hold said other running circuit switch closed independently of said pressure responsive means.

16. A liquid fuel burning apparatus comprising a burner, means for supplying liquid fuel under pressure to said burner, electrical circuit means for controlling said fuel supply means and comprising an initial circuit and an operating circuit, a closed switch in said initial circuit, an open switch in said operating circuit, means responsive to the pressure of fuel flowing from said fuel supply means to said burner and operable to open said initial circuit switch and to close said operating circuit switch, releasable means operable, upon actuation of said pressure responsive means, to hold said operating circuit switch closed independently of said pressure responsive means, and means to return said switches to their initial positions upon release of said holding means.

17. A liquid fuel burning apparatus comprising a burner, means for supplying liquid fuel under pressure to said burner, electrical circuit means for controlling said fuel supply means and com-

11

prising an initial circuit and an operating circuit, means to control said initial circuit, an open switch in said operating circuit, means responsive to the pressure of fuel flowing from said fuel supply means to said burner and operable to close said operating circuit switch, means to hold said operating circuit switch closed independently of said pressure responsive means, and said holding means including a circuit subject to the control of said initial circuit controlling means.

18. Means for controlling the operation of a fuel supply pump for a liquid fuel burner comprising starting circuit means having a normally closed switch, running circuit means having a normally open switch, means responsive to fuel pressure, means operable by said responsive means at a predetermined pressure to open said starting switch and to close said running switch; releasable means operable, upon actuation of said pressure responsive means, to hold said switches in responsive means actuated position irrespective of decrease of pressure below said predetermined pressure, and means to return said switches to their initial positions upon release of said holding means.

19. Means for controlling the operation of a fuel supply pump for a liquid fuel burner comprising starting circuit means having a normally closed switch, running circuit means having a normally open switch, a switch controlling said starting and said running circuit means, means responsive to fuel pressure, means operable by said responsive means at a predetermined pressure to open said starting switch and to close said running switch, means operable to hold said switches in responsive means actuated position irrespective of decrease of pressure below said predetermined pressure, and said holding means including a circuit responsive to the control of said control switch.

20. Means for controlling the operation of a fuel supply pump for a liquid fuel burner comprising starting circuit means having a normally closed switch, running circuit means having a normally open switch, holding circuit means having a normally open switch and a relay coil, means responsive to fuel pressure and operable at a predetermined pressure to open said starting switch and to close said running switch and said holding switch, and said relay coil being operable upon closing of said holding switch to hold said holding switch and said running switch in pressure actuated position irrespective of decrease of fuel pressure below said predetermined pressure.

21. Means for controlling the operation of a fuel supply pump for a liquid fuel burner comprising starting circuit means having a normally closed switch, running circuit means having a normally open switch, holding circuit means having a normally open switch and a relay coil, a control switch controlling said circuit means, means responsive to fuel pressure and operable at a predetermined pressure to open said starting switch and to close said running switch and said holding switch, said relay coil being operable upon closing of said holding switch to hold said holding switch and said running switch in pressure actuated position irrespective of decrease of fuel pressure below said predetermined pressure, and said control switch controlling said holding circuit means so that upon opening said control switch said relay coil may be deenergized

12

to release said switches to the control of said pressure responsive means.

22. Means for controlling the operation of a fuel pump and an electric ignition for a liquid fuel burner comprising a pump starting circuit, an ignition circuit, a pump running circuit, closed switches in said starting and ignition circuits, an open switch in said running circuit, means responsive to fuel pressure and operable at a predetermined pressure to open said starting and ignition circuit switches and to close said running circuit switch; releasable means operable, upon actuation of said pressure responsive means, to hold said running circuit switch closed irrespective of drop in fuel pressure below said predetermined pressure, and spring means for opening said running circuit switch upon release of said holding means.

23. Means for controlling the operation of a fuel pump and an electric ignition for a liquid fuel burner comprising a starting circuit having a normally closed switch, an ignition circuit having a normally closed switch, a running circuit having a normally open switch, a holding circuit having a normally open switch and a relay coil, means responsive to fuel pressure and operable at a predetermined pressure to open said starting and ignition circuit switches and to close said running and holding circuit switches, and said relay coil being operable upon closing of said holding circuit switch to hold said holding circuit switch and said running circuit switch closed irrespective of drop in fuel pressure below said predetermined pressure.

24. Means for controlling the operation of a fuel pump and an electric ignition for a liquid fuel burner comprising a starting circuit, a running circuit, an ignition circuit, a holding circuit, a control switch for controlling energization of all of said circuits, a relay switch having a pair of closed contacts in said starting circuit and a pair of open contacts in said running circuit, a circuit for the coil of said relay switch including an electron tube adapted for control by a flame-responsive photo-electric cell so that said relay switch may be responsive to the occurrence of flame at the burner, a second closed switch in said starting circuit, a second open switch in said running circuit, a closed switch in said ignition circuit, an open switch in said holding circuit, a fuel pressure responsive means operable at a predetermined pressure to open said second starting switch and said ignition switch and to close said second running switch and said holding switch, a relay coil in said holding circuit operable to be energized by closing of said holding switch and operable to hold said holding switch and said second running switch closed irrespective of drop in fuel pressure below said predetermined pressure, and said first-named control switch controlling said holding circuit so that upon opening of said control switch said relay coil may be deenergized and thereby releasing said last-named switches to the control of said pressure responsive means.

25. A liquid fuel burning apparatus comprising a burner, means for supplying liquid fuel under pressure to said burner, electrical circuit means for controlling said fuel supply means and comprising an initial circuit and an operating circuit, means responsive to the occurrence of flame at said burner and operable to control said operating circuit, a switch spring biased to open position in said operating circuit, means responsive to the pressure of fuel flowing from said fuel

supply means to said burner and operable to close said operating circuit switch, and means, operable upon actuation of said pressure responsive means, to hold said operating circuit switch closed against its opening bias independently of said pressure responsive means and in cooperation with said flame responsive means to establish said operating circuit.
